A. CROCHERON.

POCKET FOR GREASE CANS.

(Application filed Nov. 29, 1898.)

UNITED STATES PATENT OFFICE.

ALDEN CROCHERON, OF SALT LAKE CITY, UTAH.

DESIGN FOR A POCKET FOR GREASE-CANS.

SPECIFICATION forming part of Design No. 30,110, dated January 31, 1899.

Application filed November 29, 1898. Serial No. 697,796. Term of patent 14 years.

To all whom it may concern:

Be it known that I, ALDEN CROCHERON, of Salt Lake City, in the county of Salt Lake and State of Utah, have invented and produced 5 a new and original Design for a Pocket for Grease-Cans, of which the following is a full, clear, and exact description.

Reference is to be had to the accompanying drawings, forming part of this specification, 10 in which—

Figure 1 is a face or outside view of the attachment illustrating my design. Fig. 2 is a rear or inside view of the same, and Fig. 3 is a vertical section of the same on the line 3 3, 15 Fig. 1.

The design comprises the configuration of the pocket B, in which appears a tongue B',

emanating from an upper edge of the pocket B and extending downward in a curved line within the pocket, as is best seen in Fig. 3, 20 the lower end of the tongue terminating in an upwardly-extending tip B², the latter appearing through an aperture B³ in the pocket and lying against the outer face of the same.

The leading feature of the design consists in 25 the pocket, from whose upper edge emanates a downwardly-extending curved tongue.

I claim—

The design for a pocket for grease-cans, as herein shown and described.

ALDEN CROCHERON.
